UNITED STATES PATENT OFFICE.

BURTIS WILLIAM BENBOW, OF EUREKA, CALIFORNIA.

RECORDING-COMPASS.

1,216,201.

Specification of Letters Patent. Patented Feb. 13, 1917.

Application filed July 20, 1916. Serial No. 110,361.

To all whom it may concern:

Be it known that I, BURTIS WILLIAM BENBOW, a citizen of the United States, residing at Eureka, in the county of Humboldt and State of California, have invented certain new and useful Improvements in Recording-Compasses; and I do declare the following to be a full, clear, and exact description of the invention, such as will enable others skilled in the art to which it appertains to make and use the same.

My invention relates to recording compasses of the type disclosed in my co-pending U. S. patent application, Serial No. 15 96,899, filed May 11, 1916.

The object of the invention is to improve upon the construction shown in the application referred to, to such an extent as to greatly simplify the device without in any 20 manner decreasing the efficiency thereof.

With this general object in view, the invention resides in certain novel features of construction and in unique combinations of parts to be hereinafter fully described and 25 claimed, the descriptive matter being supplemented by the accompanying drawings which constitute a part of this application, and in which:

Figure 1 is a vertical section of the improved compass with the needle thereof in 30 its normal raised position;

Fig. 2 is a similar view with the needle lowered for recording upon a dial;

Figs. 3 and 4 are horizontal sectional 35 views taken on the planes of the lines 3—3 and 4—4 of Fig. 1;

Fig. 5 is a similar view on the plane of the line 5—5 of Fig. 2;

Fig. 6 is a view similar to Fig. 5 but 40 showing the operating member reversed; and

Fig. 7 is a perspective view of the operating member.

In specifically describing the structure 45 shown in the drawings above briefly described, similar characters will be employed to designate corresponding parts throughout the several views and reference will be herein made to the numerous elements by 50 their respective indices. To this end, the numerals 1 and 2 designate upper and lower sections of a comparatively flat cylindrical casing 3, these sections being detachably connected in any suitable manner such as 55 by bayonet slots 4 and pins 5. The lower section 2 is provided with a top 6 which

serves as a partition to divide the casing into upper and lower compartments, while the upper section 1 is equipped with a transparent cover 7 preferably of glass.

The center of the top or partition 6 is provided with an upright bearing 8 in which a vertically disposed staff or shaft 9 is rotatably and slidably mounted, the upper end of said shaft being pointed at 10 for engagement without friction with a jewel bearing 11 carried by the upper end of a sleeve 12 which surrounds said shaft in spaced relation thereto. The sleeve 12 rises from the center of a magnetic compass 70 needle 13 whose two halves are slotted longitudinally as shown at 14.

Slides 15 are mounted in the slots 14 and provided with openings through which worms or screws 16 are threaded, said worms 75 being rotatably mounted in any suitable manner and being housed within the slots as shown. One slide 15 carries a marking device 17 which is adapted to record certain data upon a dial 18 clamped between the 80 two sections 1 and 2 and resting on the partition 6. The other slide 15 carries a counterbalance 19 and by means of its worm 16, this counterbalance will be moved inwardly or outwardly along the needle according to 85 the manner in which the marking device 17 is shifted, said marking device being intermittently moved along the needle to place a record on the dial, the entire needle being moved downwardly at spaced intervals to 90 permit this to take place.

One of the worms 16 has secured at its inner end a combined spur and beveled gear 20, while the other is equipped with a spur gear 21, the two gears being operatively 95 connected by means of a short shaft 22 rotatably mounted within the sleeve 12 and equipped with pinions 23. The beveled portion of gear 20 is adapted for coöperation with a beveled gear 24 secured on the staff 9, this staff being successively lowered and rotated. The result of this operation is that the gear 24 will drive the gear 20 and the latter will in turn rotate the gear 21, through the instrumentality of the shaft 22 100 and pinions 23. This will move both slides 15 along the needle toward the center or ends thereof according to the direction in which the staff is rotated. Downward movement of said staff permits the entire needle 13 to rest upon the counterbalance 19 and the marking device 17, and it will 105 110

thus be evident that as the slides are moved, said device 17 will place a recording mark upon the dial 18. The lower end of the staff 9, which end is disposed beneath the 5 partition 6, carries a pinion 25 and rests on an operating member 26, said member being in the form of a horizontal disk having on its upper side a plurality of arcuate inclined cams 27 which are adapted to successively raise and permit lowering of the 10 staff 9 as said member 26 is slowly rotated by means to be described. The upper end of each cam 27 is formed with a notch 28 opening onto the lower end of the next cam, 15 and projecting into the opposed sides of these notches are teeth 29 and 30. As the member 26 rotates its numerous cams 27 will successively raise the staff 9 and it will then permit lowering thereof, since the 20 pinion 25 will drop into the notches 28 at the upper ends of said cams. As the member 26 now continues to rotate, one or the other of the teeth 29 and 30 will engage the teeth of said pinion 25 and will thus 25 turn it a fraction of a revolution while the staff is in its lowered position. Since the gear 24 is now in mesh with the beveled part of gear 20, rotation of the staff by the pinion 25 will drive said gear 20 to produce 30 the results above described; namely, moving both slides 15 along the needle.

The operating member 26 is mounted upon a vertical shaft 31 which at the point 32 is rotatably supported upon the bottom 35 of the casing section 2 in such a manner as to permit said shaft to tilt to a slight extent. The upper end of shaft 31 is similarly mounted within a bearing 33 on the inner end of a reversing lever 34 which 40 extends through a slot in the casing section 2, said lever being fulcrumed near its inner end as indicated at 35. When the lever 34 is moved in one direction, the operating member 26 will be in position to cause its 45 outermost series of teeth 29 to engage the pinion 25, thus rotating said pinion in one direction, but when said lever is swung to an opposed position, the member 26 will be so shifted as to cause the inner teeth 30 to 50 coöperate with the pinion, and thus the latter will be rotated in the reverse direction. The shaft 31 may be driven in any preferred manner from a common type of horologe 55 36 mounted in the lower section 2 of the casing 3, but for illustrative purposes, a gear 37 is shown meshing with a pinion 38 on said shaft, said gear 37 being driven at the required speed and in any suitable manner from the horologe 36.

60 A resilient slide bar 39 is mounted in a bracket 40 which depends from the partition 6 and at its outer end is provided with a finger piece 41 by means of which it may be shifted longitudinally. The inner end of 65 the bar 39 is bifurcated at 42 and straddles

the staff 9 in contact with the upper end of the pinion 25, the resiliency of said bar serving to force said pinion downwardly when the notches 28 are encountered. The bar 39 is depressed as shown at 43 between its inner end and the bracket 40, and when said bar is pulled outwardly by means of its finger piece 41, the portion 43 will serve as a cam to raise the bifurcated inner end 42, thus relieving it from engagement with the pinion 25 and moving said end outwardly to such an extent as to permit said pinion to move upwardly through the bearing 8 when the two sections of the casing 3 are disconnected.

In use, a dial such for instance as that shown in my co-pending application above referred to will be clamped between the upper and lower sections of the casing 3 in contact with the partition 6, and the worms 85 16 will be turned manually to set the marking device 17 at the time on which the voyage or journey is to begin. Said worms may be turned by application of a key or the like to the squared end 44 of one of said worms, and the correct position of the marking device 17 will be ascertained by the time scale 45 on one side of the needle 13. As the voyage or journey now proceeds, the needle 13 will be successively lowered to 90 bring the marking device 17 into contact with the dial 18, and when this takes place said marking device as well as its counterbalance 19 may move along the needle in one direction. The device 17 thus marks 100 the dial at predetermined intervals, the location of these marks varying according to the amount in which the body carrying the device turns toward different points of the compass. It will thus be obvious that the 105 course taken will be accurately plotted on the dial 18.

When retracing a course made in the manner just described, the dial 18 will be reversed by disconnecting and reversing the 110 two sections of the casing 3. The indicator 17 will then, at the beginning of the return trip, be disposed on the mark last made, and the lever 34 will be reversed to cause the operating mechanism of the device 17 to 115 move out in the opposite direction.

From the foregoing taken in connection with the accompanying drawings, it will be observed that the device is much more simple than that shown in my co-pending application, and yet that it will be equally as efficient. It will be understood that by driving the operating member 26 at a greater or less speed, or by providing said member with more or less cams 27, the number of 120 marks made per hour may be varied, the arrangement being preferably such as to cause said device to place sixty lines per hour on the chart.

In the accompanying drawings I have 125

shown a number of specific details of construction for illustrative purposes, and in the foregoing these details have been described, but it is to be understood that within the scope of the invention as claimed, numerous changes may be made without sacrificing the principal advantages thereof.

I claim:

1. In a recording compass, the combination of a dial, a compass needle movable over said dial, a staff upon which said needle is mounted, a movable member having means which serves alternately to permit the staff to lower and to then return said staff to its normal position, said staff resting on said member and a marking device carried by the needle to be brought into contact with the dial when said needle is lowered.

2. In a recording compass, the combination of a dial, a compass needle movable over said dial, a staff upon which said needle is mounted, a movable member having means which serves alternately to permit the staff to lower and to then return said staff to its normal position, a marking device carried by the needle to be brought into contact with the dial when said needle is lowered, means operable upon rotation of the staff for moving said marking device along the needle, and coacting means on said staff and movable member for rotating the former when lowered.

3. In a recording compass, the combination of a dial, a compass needle movable over said dial, a staff upon which said needle is mounted, a movable member having means which serves alternately to permit the staff to lower and to then return said staff to its normal position, a marking device carried by the needle to be brought into contact with the dial when said needle is lowered, means operable upon rotation of the staff for moving said marking device along the needle, a pinion on said staff, and one or more driving teeth on said movable member for engagement with said pinion to rotate the staff when lowered.

4. In a recording compass, the combination of a dial, a compass needle movable over said dial, a staff upon which said needle is mounted, a movable member having means which serves alternately to permit the staff to lower and to then return said staff to its normal position, a marking device carried by the needle to be brought into contact with the dial when said needle is lowered, means operable upon rotation of the staff for moving said marking device along the needle, a pinion on said staff, means on the movable member for rotating said pinion in either direction when the staff is lowered, and means for shifting said member to throw either rotating means into operation.

5. In a recording compass, the combina-

tion of a dial, a compass needle movable over said dial, a staff upon which said needle is mounted, a rotary member mounted on a vertical axis and having means which serves to raise the staff at intervals and to then release said staff to permit it to lower, a marking device carried by said needle to be brought into contact with the dial when said needle is lowered, means operable upon rotation of the staff for moving said marking device along the needle, and coacting means on the staff and rotary member for rotating said staff when lowered.

6. In a recording compass, the combination of a dial, a compass needle movable over said dial, a staff upon which said needle is mounted, a rotary member mounted on a vertical axis and having an inclined cam which serves to raise the staff at intervals and to then release said staff to permit it to lower, a marking device carried by said needle to be brought into contact with the dial when said needle is lowered, means operable upon rotation of the staff for moving said marking device along the needle, a pinion on the lower end of the staff, an inner and an outer tooth at the rear end of the cam to engage said pinion as the staff drops from the cam, and means for shifting the rotary member transversely of its axis to permit either the inner or the outer tooth to engage the pinion to drive it in either direction.

7. A recording compass comprising a dial, a compass needle which alternately moves downwardly toward and upwardly from said dial, said needle being supported between its ends, a marking device on one end of said needle for recording on the dial when said needle lowers, and a counterbalance on the other end of said needle; in combination with a pair of screws for simultaneously moving said marking device and counterbalance along the needle, and means for rotating said screws when the needle is lowered.

8. A recording compass comprising a dial, a compass needle above said dial, a staff upon which said needle is supported between its ends, a marking device on one end of the needle and a counterbalance on the other end thereof; in combination with a pair of worms for moving said marking device and counterbalance simultaneously along the needle, gear means for driving said worms from the staff when the latter is rotated, and means for intermittently permitting said staff to lower, said means including means for rotating said staff when the latter is lowered.

9. A recording compass comprising a dial, a compass needle above said dial, a staff upon which said needle is supported between its ends, a marking device on one end

4
of the needle and a counterbalance on the other end thereof; in combination with a pair of worms for moving said marking device and counterbalance simultaneously 5 along the needle, gear means for driving said worms from the staff when the latter is rotated, a disk below said staff and mounted for rotation on a vertical axis, means for rotating said disk, a plurality of cams on 10 said disk for alternately permitting the staff to lower and then returning said staff to its normal position, a pinion on the lower end

of said staff, and teeth adjacent the upper ends of the cams for engagement with said pinion as the staff drops from said cams, whereby rotation of the disk will partly rotate the staff. 15

In testimony whereof I have hereunto set my hand in the presence of two subscribing witnesses.

BURTIS WILLIAM BENBOW.
